UNITED STATES PATENT OFFICE.

GEORGE MELVILLE MCCLAIN, OF ROCKPORT, MASSACHUSETTS.

IMPROVEMENT IN TRAVELERS FOR VESSELS.

Specification forming part of Letters Patent No. 121,643, dated December 5, 1871.

To all whom it may concern:

Be it known that I, GEORGE MELVILLE MCCLAIN, of Rockport, in the county of Essex and State of Massachusetts, have made a new and useful invention having reference to the Jib-Rails and Travelers of Navigable Vessels; and do hereby declare the same to be fully described in the following specification and represented in the accompanying drawing, of which—

The traveler A in this case is a ring provided with a stirrup or yoke, a, to receive a slide-block, B, and turn in a notch, b, made therein. The ring has an eye, c, by which it may be fastened to the corner of the jib.

Figs. 3 and 4 are transverse sections of the traveler and slide-block.

The rail on which the traveler runs is shown at C as a round bar supported above the deck E by standards F F, and provided with two elastic stops or projections, D D, of India rubber, which, arranged at the terminus of the range of motion of the traveler on the rail, serve to arrest the ring and prevent breakage of its eye and the seizings of the ring to the sail.

I make no claim to anything described or shown in either of the United States patents 43,150, 31,759, or in Haskins & Manning's application for a patent allowed October 13, 1869.

I claim—

The traveler as made with the stirrup or yoke to receive and hold the slide-block and with the eye for connecting the traveler to a jib, all as described, in combination with the said slide-block, arranged with and notched upon the yoke, as set forth.

GEORGE MELVILLE MCCLAIN.
